UNITED STATES PATENT OFFICE.

MANUEL MONDRAGON, OF TACUBAYA, MEXICO.

BREECH MECHANISM FOR ORDNANCE.

SPECIFICATION forming part of Letters Patent No. 537,701, dated April 16, 1895.

Application filed April 21, 1894. Serial No. 508,474. (No model.) Patented in France November 18, 1891, No. 217,526.

To all whom it may concern:

Be it known that I, MANUEL MONDRAGON, a citizen of the Republic of Mexico, residing at Tacubaya, in the Federal District of Mexico, have invented certain new and useful improvements in Breech-Loading Cannon, (for which I have obtained a patent in France, No. 217,526, dated November 18, 1891;) and I do hereby declare the following to be a full, clear, and exact description of the invention, such as will enable others skilled in the art to which it appertains to make and use the same.

My invention has relation to breech blocks, which are operated to unlock, withdraw and open by a single pull of an operating lever, said lever being pivoted on the carrier and its projecting end engaging a cam slot in the face of the breech block, whereby the breech block is unlocked by the first part of the motion of the operating lever. I also provide safety mechanism for protecting the firing pin, during the time in which the breech block is unlocked, which mechanism consists of a projecting shutter hung on a shaft journaled in the carrier, and means for operating said shaft upon the revolution of the breech-block.

To accomplish this object my invention consists in the features of construction and arrangement of parts, hereinafter described and claimed.

is illustrated in the accompanying drawings, in which—

Figure 1 is a horizontal section, the breech-block being in elevation. Fig. 2 is a similar view, the breech-block thrown open. Fig. 3 is a rear view, the parts being in the position as shown in Fig. 1. Fig. 4 is a side elevation. Figs. 5 and 6 are detail views. Figs. 7 and 8 are detailed views showing the cams, in their operative and inoperative positions;

In order to enable those skilled in the art to make and use my invention, I will now describe the same in detail, referring to the drawings, wherein—

A indicates a gun; a', the tube, and a², the set thereof, the same being equipped with my improvements.

B is the breech-block, having what I shall term for convenience a double set of interrupted screw threads, b, b', engaging corresponding screw threads, b¹ in the gun, the

threads, b', being on a line with the spaces, b², of the outer threads, b, as will be seen by reference to the drawings, so that the breech-block can be easily withdrawn.

55

The breech-block has a reduced portion, c³, on its outer end which forms the axis for it to revolve on. This reduced portion is pivotally supported by the carrier arm, C, which is horizontally pivoted between ears, c⁴, by a pin, c⁵, on one side and near the breech of the gun. The carrier arm and the reduced portion, c³, are connected by means of a screw, V, passing through a perforation in the end of the carrier arm and entering an annular groove, V', in the reduced portion. A slight bend in the arm, C, as at c⁶, is necessary so that ready access may be had to the firing pin.

Through a central perforation in the breech-block extends the firing pin, K, operated by any suitable means (not shown). In the outer face of the breech-block is formed a cam slot c⁷, extending nearly at right angles to a vertical line from the center of the gun.

In a slot, c⁸, in the carrier arm is mounted 75 on a pin, c⁹, a lever, G, having a reduced inner end, as at g. The outer end of said lever has formed thereon an operating handle, T, hollowed out at t', forming a seat for a bell-crank latch, t, the horizontal arm of which 80 has a step, t'', which engages a bevel projection, a'', on the side of the gun. A small spring t³, serves to keep the step, t'', in engagement with the projection, a, thus locking the parts together. In the carrier arm is 85 mounted a short shaft, J, having at its inner end a cam, f', seated in a crank arm slot, f, in the front face of the breech-block, and at its outer end a shield or guard, J'.

In the rear of the carrier arm is formed a 90 recess, c¹⁰, and seated therein is a spring, c¹¹, having on its outer face two lugs, b⁵ and b⁶. A small indentation, b⁷, is formed in the outer face of the breech-block and in the path of the lug, b⁶. When the breech block is 95 returned to the breech, the lug b⁵, comes in contact with the end of the gun, pressing in the spring arm on which is formed the lug, b⁶, thus disengaging the lug, b⁶, from the notch, b⁷, in the breech block and permitting said 100 breech block to turn.

The end of the carrier arm has a project-

ing lug, b^{10} , that is so arranged as to strike against and withdraw the extractor.

The operation of my device is as follows, the parts being in position as shown in Fig. 5 1: The operator grasps the handle, T, at the same time pulling in the direction of the arrow, 1, which releases the latch and revolves the latch-block one-twelfth of a revolution. The lever, G, is prearranged so as to revolve 10 the breech-block far enough to bring the screw threads on said breech-block directly in line with the spaces between the threads on the interior of the gun. It will be understood that motion is imparted to the breech-block by means of the lug, of the lever, G, operating in the cam slot. The shaft, J, on which the crank arm, f' , is secured, revolves in bearings in the carrier, G. It will be readily seen that as the breech block is revolved the 15 lower portion f^5 of the cam f , in the face of the breech block will come in contact with the lower portion f^{16} of the crank arm and revolve the shaft far enough to throw up the guard, J', and protect the firing pin. The 20 first motion of the lever disengages the latch, revolves the breech-block into such a position that it may be readily withdrawn and throws up the shield. The motion is continued and from this point of the operation, 25 the lever G, carrier arm, and breech-block move as one, the parts now traveling in the direction of the arrow, 2, and the breech-block is withdrawn from the breech as shown in Fig. 2. As the breech-block leaves the 30 breech, the lug, b^6 , on the spring, engages the indentation, b^7 , and securely locks the carrier arm and the breech block together. Thus when the parts are returned no danger of the 35 screw threads on the breech-block coming in 40 contact with the interior threads of the gun, will be encountered. At a given time the lug on the lever G, comes in contact with the extractor and withdraws it from the gun.

All the parts are so arranged and constructed that by reversing the movement of 45

the lever, the breech-block can be replaced within the breech, by a single movement.

It will be seen that I have provided a breech mechanism that is extremely simple in construction and that can be operated in less 50 time than has heretofore been necessary. A single movement withdraws the breech-block, and a single movement returns it.

My invention will be readily understood by those skilled in the art to which it pertains. 55

Having thus described my invention, what I claim is—

1. In a gun having a breech block, provided on its outer face with a cam slot, in combination with a carrier arm, an operating lever 60 pivotally connected to said carrier arm, the end of said lever working in said slot, substantially as shown and described.

2. In a gun the combination with a breech block and carrier arm of a shaft journaled 65 in said arm and provided with a crank arm, a shield, or guard, on the opposite end of said shaft a cam slot in the breech block to receive said crank arm, the firing pin covered by said shield, and by the carrier arm and lever, 70 whereby the firing pin is covered or uncovered, when the gun is opened or closed, substantially as described.

3. In a gun, the combination with a carrier arm, a hinged breech block having on its 75 outer face a cam slot, an operating lever hinged to the carrier arm, provided with a lug engaging the cam slot in the face of the breech block, a shaft journaled in the carrier arm, having at its outer end a guard or 80 shield, and its inner end provided with a crank arm seated within and operated by the cam slot in the face of the breech block, substantially as described.

In testimony whereof I affix my signature 85 in presence of two witnesses.

MANUEL MONDRAGON.
